BY

John A. Seifert

ATTORNEY

UNITED STATES PATENT OFFICE

2,430,124

WINDOW

Ethel S. Johnson, Flushing, N. Y.

Application December 29, 1944, Serial No. 570,320

1 Claim. (Cl. 20—52)

1

This invention relates to auxiliary closures for windows, such auxiliary closures constituting either storm windows or screens for said windows and being particularly adapted for use with casement windows whereby the adjustable portion or portions of the casement window may be readily actuated to open or close positions without interference by the auxiliary closure.

It is the principal object of the invention to produce an auxiliary closure, particularly a storm window, which presents no obstructions to the view through the window.

It is another object of the invention to provide a storm window for a casement window which permits ventilation equivalent to that which ordinarily enters an open casement window.

It is a further object of the invention to provide an auxiliary closure which is readily positioned in and removed from a mounting frame therefor whereby one type of closure may be readily replaced by another type of closure or the closure may be readily removed for cleaning and replaced when clean.

Another object of the invention is to provide a storm window for any type of window in which the storm window has no cross bars which will obstruct the view through the window and facilitate cleaning of said storm window.

A further object of the invention is to provide an auxiliary closure which requires only a minimum amount of storage space.

A still further object of the invention is to provide a mounting frame for a storm window mounted in insulated relation to a casement window frame and arranged to adjustably support the storm window and weather insulate the same, and also permit the mounting of the storm window without interfering with an ordinary screen for the casement window.

Further objects and advantages of the invention will appear in the detailed description of the invention.

The embodiment of the invention comprises a mounting frame having a pair of parallelly extending grooves or channels in the inner faces of the side and bottom members thereof and a single channel in the inner face of the top member with a separator of resilient material mounted in said single channel to form a double channel

2

in the top frame member with a resilient separating wall to facilitate mounting of panels either of glass or wire mesh screen into the top and bottom frame members and yieldingly retain the panels in a vertical plane. The panels are slidably supported by the channels in the bottom frame member and guided by the channels in the top frame member and in window closing position, the outer side portions of certain panels will engage in the channels in the side frame members with the inner side portions of said panels overlapping each other if there are only two panels or overlapping the side portions of another panel if there are more than two panels. The mounting frame is mounted in weather insulated relation with the window frame and the overlapping side portions of the panels are also weather sealed. The members of the mounting frame are interlocked with each other at the corner portions thereof.

In the drawings accompanying and forming a part of this application,

Figure 1 is an elevational view of an auxiliary closure in full window closing position looking at the interior thereof.

Figure 2 is a cross sectional view taken on the line 2—2 of Figure 1 looking in the direction of the arrows and showing the relationship between the auxiliary closure and a permanent window.

Figure 3 is a longitudinal sectional view taken on the line 3—3 of Figure 1 looking in the direction of the arrows.

Figures 4, 5 and 6 are fragmentary perspective views, on an enlarged scale, of the top member of a mounting frame for the closure showing the progressive steps of engaging a panel of the closure in the mounting frame.

Figure 7 is a fragmentary sectional view on the longitudinal axis of the top frame member showing the manner of insulating and securing said member in a window frame.

Figure 8 is a fragmentary sectional view in perspective of a side frame member showing the manner of insulating and securing said member in a window frame.

Figure 9 is a fragmentary perspective view of a side portion of a panel carrying a weather strip to seal the space between a plurality of panels.

Figure 10 is a fragmentary perspective view of

50

an end portion of a modified form of weather strip to be carried by a side portion of a panel as shown in Figure 9.

Figure 11 is a fragmentary end view of overlapping side portions of a pair of juxtaposed panels, each panel carrying a modified form of weather stripping.

Figure 12 is a sectional view of the upper end portion of a side frame member showing a tongue for engaging in a channel of the top frame member to connect the side frame members with the top frame member.

Figure 13 is a sectional view of an end portion of the bottom frame member showing a tongue for engaging in a channel of the adjoining side frame member to connect the bottom frame member with the side frame members.

Figure 14 is a fragmentary sectional view of a side portion of a panel showing the mounting of a finger grip actuating member thereon.

Figure 15 is a plan view of the finger grip actuating member shown in Figure 14.

Figure 16 is a composite view of the frame members looking at the ends of said members to show the actual size and shape of the members relative to each other.

Figure 17 is an end view of a modified form of a separator member having the free edge portion arranged with a strip of felt.

Figure 18 is a view similar to Figure 7 and showing a modified manner of securing an insulating strip to the top frame member.

Figure 19 is a view similar to Figure 16 and showing the frame members formed of wood pieces.

Figure 20 is a view of a corner connection between the top and side frame members looking at the outer face of the side frame member and at the end of the top frame member.

Figure 21 is a view of a corner connection between the side and bottom frame members looking at the outer face of the bottom frame member and at the lower end of the side frame member.

The present invention is adapted to be used as an auxiliary closure for all types of windows and particularly for a casement window, as indicated at 17 in Figure 2, mounted in the usual manner in a frame 18.

The auxiliary closure comprises a mounting frame mounted in the frame 18 at either side of the window 17 and shown in the present illustration as being mounted at the inside of the window. Said frame consists of top, side and bottom members 19, 20, and 21, respectively, formed of suitable material, such as wood or metal, and arranged for the slidably mounting of panels 22, 23 of either glass or screen or wire mesh. There are shown only two panels but more than two panels may be used as will be described herein-after.

The top frame member 19 is shown in the present illustration of the invention to be formed from a single strip or longitudinal piece of suitable pliable and relatively stiff material, such as metal, to channel shape in cross section having the opposite marginal portions folded upon themselves, as shown at 24, and said folded portions bent at a right angle to the intermediate or middle portion of the member to form a single channel 25. The channel 25 is divided into two equal parts or channels by a separator comprising a pair of right angle members of suitable resilient material, such as sheet metal, with one leg portion 26 engaged on the inner surface of the bottom wall portion of the channel 25 with the other

leg portions 27 extending into the channel 25 in juxtaposed relation with each other and parallelly of the folded portions 24 of the top frame member 19 and having the free edge portion folded upon the outer face to form a bead 28 projecting slightly in a diverging direction and terminating in horizontal alignment with the fold of the folded portions 24, as shown in Figures 4 to 6, inclusive.

In place of the folded over bead 28, a strip of felt 29 may be secured to the outer surface of each leg portion 27 adjacent to the free edge thereof, as shown in Figure 17. The purpose of the resilient separator will be fully disclosed in the description relative to the mounting of the panels 22, 23 in the frame members 19, 20 and 21. The top frame member 19 is secured to the upper or top member of the window frame 18 and the joint between said frame members is insulated from the weather by a layer 29 of insulating material, such as felt interposed between the exterior surface of the bottom wall portion of the channel 25 and the top member of the window frame 18 and by screws 30 engaged in aligned openings punched in an outwardly direction from the leg portions 26 of the separator and the bottom wall portion of the channel 25 with the punched material extending into the insulating material, as shown at 31 in Figure 7, which will unite the insulating material and the top frame member 19. The insulating material may also be adhesively united to the member 19, as indicated at 32 in Figure 18. The top frame member may also be made of a longitudinal piece of wood 61 having the groove or channel 25 extending longitudinally in the center thereof with the resilient separator 26, 27 mounted in the groove in the same manner as the metallic member 24, as shown in Figure 19.

The side frame members 20 are similar in structure and also formed from a single longitudinal piece or strip of metal with the opposite marginal portions folded upon themselves and extended at a right angle from a face of the strip, as shown at 32 in Figures 8 and 16, and a center portion of the strip is also folded upon itself or drawn to loop formation, as shown at 33, whereby the folded portions 32 and 33 form a pair of parallelly extending grooves or channels 34, 35. The side members are secured and insulated in the side members of the window frame 18 in the same manner as the top frame member 19, as by a layer 36 of insulating material and screws 37 engaged in holes in the bottom wall portion of the channels 34, 35 and extended through the layer 36 of insulating material into the side members of the window frame 18. The heads of the screws 37 are countersunk below the inner surface of the bottom wall portions of the channels 34, 35 by chamfering the openings in said wall portions, so that a layer 38 of insulating and resilient material, such as felt, may be secured to the exposed inner surface of the bottom wall portions of the channels 34, 35, as by a suitable adhesive, whereby the side portion of the panels 22, 23 engaged in the channels 34, 35 is weather sealed and any shock caused by striking the panels against the side frame members 20 is absorbed by said layer 38. The side frame members 20 are connected to the top frame member 19 by tongues 39 extending from the upper end portions of the side frame members 20 and engaging in the spaces between the folded portions 24 of the top frame member 19 and the separator leg portions 27, and said tongues 39 are formed by extending the bottom wall portions of the channels 34, 35, as shown in Figures 12 and 20. The side frame members

20 may be constructed of a strip of wood 62 having a central groove or channel of a width equal to the distance between the folded portions 32 and the channels 34, 35 are formed by a strip 63 of metal of T-shape in cross section with the cross member secured to the bottom wall portion of the groove and the leg portion of said strip extending into the groove and constituting the folded portion 33, as shown in Figure 19.

The bottom frame member 21 is similar in cross sectional shape to the side frame members 20 and formed to double channel shape in cross section by folding the opposite marginal portions upon themselves and said folded portions bent to extend at a right angle from a face of said strip, as shown at 40 in Figure 16, and the center portion of the strip is folded upon itself and extended in parallel spaced relation to the folded marginal portions 40, as shown at 41, whereby a pair of parallelly extending channels 42 are formed. The bottom frame member 21 is connected to the side frame members 20 by extending the bottom wall portions of the channels 42 to form tongues 43, as shown in Figures 13 and 21, adapted to engage in the lower end portions of the corresponding channels 34, 35 of the side members 20. The bottom frame member 21 is not secured to the bottom member or sill of the window frame 18 by securing means, such as screws, as said frame member 21 is retained on the said bottom member or sill by the weight of the other frame members 19, 20 and the panels 22, 23 and the locking engagement between the tongues 43 and the channels 34, 35, but the bottom frame member 20 is weather sealed in the frame 18 by a layer 36' of insulating material (Figures 1 and 3) adhesively secured to either or both the frame member 21 and the sill of the window frame 18. The bottom frame member 21 may also be formed of a wood strip 64 having a central groove or channel of a width equal to the distance between the folded portions 40 and the channels 42 are formed by a strip 65 of metal of T-shape in cross section with the cross portion secured to the bottom wall portions of the groove and the leg portion of said strip extending into the groove in parallel spaced relation to the side walls of the groove and constituting the folded portion 41, as shown in Figure 19.

As shown in Figure 16, the width of all the frame members is the same, but the depth of the channels in the frame members vary, the depth of the channel 25 in the top frame member 19 being slightly less than twice the depth of the channels 34, 35 in the side members 20 and slightly greater than triple the depth of the channels 42 in the bottom frame member 21, for a purpose to be described hereinafter.

The frame members 19, 20 and 21 may be assembled in the window frame 18 either by mounting and assembling the members individually in the window frame 18, or assembling the members to form the frame prior to mounting said frame in the window frame.

The layers 29, 36 and 36' of insulating material in addition to insulating the frame members 19, 20 and 21 also fill in all irregularities in the surfaces of the members of the window frame 18.

The present illustration of the invention only shows a pair of glass panels 22, 23 of slightly greater width than one-half the distance between the bottom wall portions of the channels 34, 35 in one side frame member 20 and the bottom wall portions of the corresponding channels 34, 35 in the opposite side frame member 20 and slidably

6 mounted in different channels of the frame members 19, 20 and 21, but it is possible to use three panels, each panel having a width slightly greater than one-third the distance between the bottom wall portions of the channels in the side frame members 20 and slidably mounting two of said panels in one channel of the frame members 19, 20 and 21 with the third panel slidably mounted in the other channel of said frame members. It is also possible to use four panels with each panel of a width slightly greater than one-fourth the distance between the bottom wall portions of the channels in the side members 20 and two panels being slidably mounted in the same channel of the frame members.

Regardless of the number of panels employed, the panels are readily engaged in the frame members 19, 20 and 21 by engaging the top portion of a panel in a channel in the top member 19 formed by a folded portion 24 and a leg portion 27 of the resilient separator with the panel in canted position, as shown in Figure 4, then moving the panel into said channel with the top edge of the panel abutting the leg portion 26 of the resilient separator, as shown in Figure 5, which will position the bottom edge of the panel above the top of the side wall portions of the channels 42 in the bottom frame member 21 and permit said bottom edge of the panel to be engaged in the channel 42 in vertical alignment with the channel in the top frame member engaged by the top edge portion of the panel. When the bottom edge portion of the panel is engaged in its proper channel 42, the top edge portion of the panel will assume a position in spaced relation to the leg portion 26 of the resilient separator, as shown in Figure 6. The resiliency of the separator leg portions 27 facilitates the engagement of the top portion of the panels in the top frame member 19 and retains the panels in their proper vertical plane after the bottom edge portions are engaged in the channels 42 of the bottom frame member. The beads 28 of the resilient separator will tightly engage the panels and seal the joint between the separator 45 and the panels against the weather and urge the panels against the folded portions 24 in weather sealing engagement therewith. In engaging the panels in the frame 19, 20, 21, the side portions of the panels are free of the channels 34, 35 in the side frame members 20 and said side portions of the panels are grasped by the hands of the person installing the closure. In the present illustration of the invention, the panel 22 will be installed in the frame 19, 20, 21 before the panel 23 is installed. To remove the panels from the frame 19, 20, 21 for cleaning or storing, the panel 23 is positioned in said frame with the side portions of said panel free of the channels 35 in the side frame members 20 and the panel is lifted out of the corresponding channel 42 in the bottom frame member 21 by engaging the top edge of the panel with the separator leg portion 26, as shown in Figure 5, and then the panel is canted to remove the top portion of the panel out of the top frame member 19, as shown in Figure 4. After the panel 23 is removed, the panel 22 is removed in the same manner as panel 23.

The depth of the channels 42 in the bottom frame member 21 will permit the engagement or removal of the panels without undue canting of the panels and the depth of the channel 25 in the top frame member 19 will assure the engagement of the top portions of the panels by the folded portions 24 when the bottom portions

of the panels are engaged in the channels 42 of the bottom frame member 21.

The panels are slidably supported by the bottom wall portions of the channels 42 in the bottom frame member 21 and are guided at the upper portions in their sliding movement by the folded portions 24 and the separator leg portions 21.

When it is desired to fully close the interior of the window 17, the panel 22 is moved in the top and bottom frame members 19 and 21 to engage a side portion of said panel 22 in the channel 34 of one of the side frame members 20 and the panel 23 is moved in the top and bottom frame members 19 and 21 to engage a side portion of said panel 23 in the channel 35 of the opposite side frame member 20 with the free side portions of the panels 22 and 23 in overlapping relation, as shown in Figures 1 and 2. The interior of the window 17 may be exposed to any desired degree by moving either panel toward an empty channel in the side members 20. To expose the maximum amount of the window 17, the overlapping side portion of either panel is engaged in the channel of the side member. The actuation of the panels is facilitated by a finger gripping member comprising a piece of pliable material, such as metal, having a rectangular end portion 44 arranged with an opening 45, an intermediate portion 46 having its sides diverging from the sides of the end portion 44, as shown in Figure 15, and bent at an obtuse angle from the outer face of the end portion 44, as shown in Figure 14, and the other end portion is in the form of an arrow head, as shown at 47 in Figures 1 and 15, and bent at an acute angle from the inner face of the intermediate portion 46, as shown in Figure 14. The finger gripping member is mounted on the inner face of each panel adjacent the side edge portion of the panel engaging the side members 20 in the fully close position of the panels and intermediate the top and bottom edges of the panels, as shown in Figure 1, by suitable fastening means, such as a screw engaged in the opening 45 in the finger engaging member and a corresponding opening in the panel and secured in the finger grip and panel by a nut, as shown at 48 in Figure 14. In the mounted position of the finger gripping member the juncture between the portions 46 and 47 is spaced from the panels with the free edge of the portion 47 engaging the panels, as shown in Figure 14. The finger gripping member extends from the panels a distance less than the space between the panels.

The juxtaposed faces of the panels are spaced from each other by a distance equal to the thickness of the center folded portion 33 of the side frame members 20, and this space is atmospherically sealed by suitable means carried by the overlapping side portion of one or both panels. In Figure 9, such means is shown as comprising a strip of fabric 49 folded longitudinally upon itself and having a core 50 of yielding material, such as rubber or fabric, engaged in the fold and the opposite marginal portions of the fabric 49 are juxtaposed and secured to each other, as by an adhesive. The composite sealing strip 49 and 50 is secured to the face of the panel 22 juxtaposed to the panel 23 by an adhesive or by a channel or U-shaped strip 51 of resilient material, such as metal, engaged over the edge of the overlapping side portion of the panel 22 in clamping engagement with the juxtaposed marginal portions of the strip 49. The folded

portion of the strip 49 carrying the core 50 is of a thickness greater than the space between the panels so that the folded portion of the strip will frictionally engage the juxtaposed face of the panel 23 in all of the positions of the panels.

Figure 10 discloses a modified form of the folded strip 49 and the core 50 comprising a single strip of fabric having one marginal portion 52 of greater thickness than the opposite marginal portion 53, the marginal portion 52 corresponding to the folded portion of the strip 49 and the core 50 and the marginal portion 53 corresponding to the juxtaposed marginal portions of the strip 49. The continuous face of the strip 52, 53 is engaged on the juxtaposed face of the panel 22 and secured thereto either by adhesive or the clamping strip 51.

In Figure 11, there is shown sealing means carried by the overlapping side portions of both panels and comprising a pair of longitudinal members of resilient material, such as sheet metal, one member having a body 54 of channel shape in cross section adapted to be engaged on the overlapping side portion of the panel 22 with a marginal portion bent at an acute angle to the leg portion of the body 54 engaging the juxtaposed face of the panel 22, as shown at 55, with the free edge of said portion 55 curved inwardly, as shown at 56. The other resilient member comprises a channel shaped strip of metal having a straight side and bottom portion engaging the outer face and edge of the panel 23, as shown at 51, and the other side portion curved outwardly, as at 52, to engage the curved edge 56 of the other member 54 in the fully close position of the panels. The resilient sealing members 54 and 57 are shown mounted on the free side portions of the panels having beveled edges but said members may also be mounted on square edges.

The structure of the frame members 19, 20 and 21 permits the mounting of the panels 22 and 23 without enclosing the edges of said panels in a frame and prevents drafts by having a close fit between the individual frame members and between the frame members and the panels.

The panels are shown as of glass but the panels may be in the form of screens, or each closure may consist of a set of glass panels and screen panels, the glass panels being mounted in the frame members 19, 20 and 21 during the winter months and the screen panels being mounted in said frame members during the summer months.

The closure disclosed in the application may also readily be adapted for other types of windows, such as double hung windows.

Having thus described my invention, I claim:

In an auxiliary closure for windows, a mounting frame having the side and bottom members formed from sheet material into three folded portions with the middle folded portion spaced from the outer folded portions to form a pair of parallelly extending channels and the top member formed from sheet material into two folded portions spaced from each other to form a channel and said frame members mounted in the frame of a window at a side of said window, a separator of resilient material mounted in the channel of the top member of the frame to form a pair of channels in said frame member, and a plurality of panels of less height than the height of the mounting frame and of a width less than the width of said frame, each of said panels slidably supported in a channel of the bottom member of the frame and yieldingly engaged by the separator to provide movement of the panels trans-

9

versely of the window and positioning of a side edge portion of one panel in overlapping relation to a side edge portion of another panel when the panels are in window closing position.

ETHEL S. JOHNSON.
